(57) **CLAIM**

The ornamental design for a convertible leggings, as shown and described.

DESCRIPTION

FIG. 1 is a front elevational view of a convertible leggings in a capri-length configuration, showing our new design; FIG. 2 is a rear elevational view thereof; FIG. 3 is a right side elevational view thereof, the opposite left side elevational view being a mirror image thereof; FIG. 4 is a cross-sectional view of the convertible leggings taken along line 4-4 in FIG. 2;

FIG. 5 is a front elevational view of the convertible leggings of FIG. 1 in a pant-length configuration; FIG. 6 is a rear elevational view thereof;

FIG. 7 is a right side elevational view thereof, the opposite left side elevational view being a mirror image thereof; and, FIG. 8 is a cross-sectional view of the convertible leggings taken along line 8-8 in FIG. 6.

The dot-dash-dot broken line outline of the partial human figure in the drawing disclosure assists in illustrating how the convertible leggings may appear when in a position of use, but forms no part of the claimed design. The dash-dash broken lines along the surfaces of the convertible leggings depict claimed stitching.

The cross-hatched lines in the drawings show shading that defines the contours of the convertible leggings and do not reflect a particular surface ornamentation or material.
